DESIGN FOR A SACHET BAG

Jean E. Vivaudou, New York, N. Y.

Application September 7, 1945, Serial No. 121,904

Term of patent 7 years

(Cl. D86—10)

To all whom it may concern:

Be it known that I, Jean E. Vivaudou, a subject of the King of Great Britain, residing at New York, in the county of New York and State of New York, have invented a new, original, and ornamental Design for a Sachet Bag, of which the following is a specification, reference being had to the accompanying drawing, forming a part thereof.

In the drawing:

Fig. 1 is a top plan view of a sachet bag, showing my new design;

Fig. 2 is a bottom plan view; and

Fig. 3 is a side elevational view of the same.

I claim:

The ornamental design for a sachet bag, as shown.

JEAN E. VIVAUDOU.
